ELECTRICALLY OPERATED FLUSH VALVE

John D. Andrews, Washington, D. C.

Application January 22, 1936, Serial No. 60,330

3 Claims. (Cl. 4—67)

This invention relates to electrically operated flush valves and has for an object to provide a novel solenoid and circuit closer to maintain the flush valve open until the float ball moves downward to its limit of movement upon the receding water level in the tank.

A further object is to provide a device of this character having a novel circuit maker and breaker to interrupt the flow of current to the solenoid when the float ball has reached its limit of movement to allow the flush valve to again seat in order that the tank may refill.

A further object of the invention is to provide a device of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

The figure is a diagrammatic view of the invention applied to a flush tank, the latter being shown in full lines.

Referring now to the drawing in which like characters of reference designate similar parts in the various views, a conventional flush tank is shown comprising a tank 10, a flush valve 11 controlling the flush pipe 12, the valve having a vertical stem 13 which extends through a tubular guide 14 mounted on a bracket arm 15 which projects from the overflow pipe 16.

The stand pipe 17 is connected in the usual manner to the water supply pipe 18 and is equipped at the top with a bracket 19 for pivotally mounting the stem 20 of the float ball 21. The stem is provided at the end opposite the ball with an integral arcuate finger 22 one end of which is pivoted to the bracket 19, as shown at 23, and the other end of which is adapted to impinge against the outlet valve 24 of the stand pipe and hold the valve closed when the float ball is in normal raised position.

All of the above described parts are of the conventional and well known flush tank construction.

In carrying out the invention a solenoid 25 is suitably mounted in the tank above the valve stem 13 and the latter is provided at the top with

an integral solenoid core 26. The core is slidably fitted in the solenoid and extends for the greater portion of its length below the solenoid when the valve 11 is seated. When the solenoid is energized the core is withdrawn upwardly within the solenoid and lifts the valve to permit the flushing water to escape through the flush pipe 12.

A plug 27 of non-magnetic material, such as brass for instance, is loosely mounted in the upper end of the solenoid and is provided with a stop pin 28 which bears upon the top of the solenoid and supports the plug at its lower limit of movement. The plug is provided on the top face with a switch contact 29 which is insulated from the plug by a blank 30 of insulating material.

The plug is pushed upwardly by the rising core 26 until the switch contact 29 bridges two stationary switch contacts 31 which are suitably mounted in the flush tank above the plug and insulated from the flush tank in any preferred manner. The plug forms a circuit closer to maintain the solenoid 25 energized and the valve 11 held in raised position until the flushing water has all escaped from the tank, as will presently be described in detail.

A switch 32 is slidably mounted on a rod 33 which is pivoted at the lower end, as shown at 34, on the stem 20 of the float ball 21. The switch is insulated from the rod by blanks 35 of insulating material. The switch 32 may be in the form of a single blade pivoted at one end and swingable to engage a stationary switch contact 36 when the float ball stem is in raised position, as shown in full lines, and swingable out of engagement with the switch contact when the float ball stem is in lowered position, as shown by dotted lines.

The circuit wiring is as follows. From the battery 37 a circuit wire 38 is led to the pivoted switch 35 and a circuit wire 39 is led from the switch contact 36 to one end of the coil of the solenoid. A circuit wire 40 is led from the other end of the coil of the solenoid through a push button switch 41, located exteriorly of the flush tank within convenient reach of the operator, and is connected to the battery by a circuit wire 42. When the push button 41 is closed current from the battery will energize the solenoid 25 whereupon the core 26 will be withdrawn upwardly into the solenoid to simultaneously open the valve 11 and raise the circuit closer plug 27 until the switch contact 29 bridges the stationary switch contacts 31.

One of these latter contacts is connected by a circuit wire 43 to the wire 40 and the other is connected by a circuit wire 44 to the wire 42.

Consequently when the contact 29 bridges the contacts 31 current will then flow from the battery through the wires 42, 44, 43, solenoid 25, wire 39, switch 32 and wire 38, whereby the solenoid is maintained energized and the valve 11 is maintained in raised position.

As the flushing water escapes past the open valve 11 into the flushing pipe 12 the float ball 21 will ride down upon the receiving water level 10 until it reaches a position level with the valve seat, as shown in dotted lines. At this moment the rod 33 will be lowered by the valve stem 20 sufficiently to permit a head 45 on the rod to strike the upper insulating blank 36 as the rod slides downwardly 15 through the insulating blank and the switch 32 and open the switch to the dotted line position shown. Whereupon the circuit from the battery through the solenoid will be broken at the moment the switch 32 disengages from the switch 20 contact 36 and permits the solenoid to become de-energized and allow the core 36 to drop and thereby permit the valve 11 to close by gravity as is customary.

As the core 36 drops the circuit closing plug 25 21 will likewise drop until the stop pin 28 again rests upon the top of the solenoid, at which time the circuit closer will again be in set position ready for the next operation. When the ball float rises to shut off the water valve 34 the rod 30 33 is lifted by the float stem and closes the switch 32 so that the solenoid may again be energized as above described by operation of the push button switch.

It will thus be seen that the operation of the device is positive, that the circuit closers are strong, simple and durable and are disposed considerably 35 above the water level so that their long life and durability will be promoted, and that the device may be readily installed on flush tanks now in use, 40 as well as those in the process of construction.

From the above description it is thought that the construction and operation of the invention will be fully understood without further explanation.

15 What is claimed is:

1. In a flush tank, a flush valve having an upright stem, a magnet above the stem adapted to attract the stem and open the flush valve when the magnet is energized, a manually controlled

circuit for energizing the magnet, a second circuit for maintaining the magnet energized after the manually controlled circuit is opened, switch contacts in the second named circuit, a circuit closer actuated by said stem to bridge the contacts and close the second named circuit, a ball float having a stem, and a switch in the manually controlled circuit actuated by the ball float stem to open said circuit when the ball float is at its lowest limit of movement to de-energize the magnet and permit the valve to seat whereby the tank may refill. 5 10

2. In a flush tank, a flush valve having an upright stem, a solenoid core fixed to the upper end of the stem, a solenoid receiving the core, a manually controlled circuit for energizing the solenoid, a second circuit for maintaining the solenoid energized after the first named circuit is opened, switch contacts in the second named circuit, a circuit closer loosely mounted in the solenoid above and spaced from the core, upward movement of the core when the solenoid is energized opening the flush valve and simultaneously dislodging the circuit closer upwardly to bridge said contacts and make the second named circuit, a float ball having a stem, and a switch in the first named circuit connected to the float ball stem and adapted to open said circuit when the float ball recedes to its downward limit of movement to de-energize the solenoid and permit the flush valve to seat whereby the tank may refill. 20 25

3. In a flush tank, a flush valve having a stem, a magnet for attracting the stem to open the valve, a manually controlled circuit for energizing the magnet, a second circuit for maintaining the magnet energized after the first named circuit is opened, a switch operated by upward movement of said stem to make the second named circuit, a float ball having a stem, a rod connected 35 to the stem, a pivoted switch in the first named circuit through which the rod is loosely engaged and a head on said rod above the switch, downward movement of the stem when the ball recedes moving said head to engage said switch and open the first named circuit to de-energize the magnet and permit the flush valve to seat whereby the tank may refill. 40 45
